ALBERT R. GOLDRICK, OF CLEVELAND, OHIO, ASSIGNOR TO THE GERSON STEWART CORPORATION, COMPANY, OF CLEVELAND, OHIO, A CORPORATION OF OHIO.

LIQUID-DISPENSING VALVE.

Application filed May 29, 1922. Serial No. 564,369.

This invention is directed to improvements in apparatus for dispensing liquid soap and is more particularly concerned with improvements of that type of dispenser which is used in combination with a distributing system wherein a supply reservoir is remotely positioned from the place in which the soap is dispensed or used.

The general object of the present invention is the provision of a soap dispensing valve which may be connected to a supply line or pipe wherein there is considerable pressure or head; the movable elements of the valve being such that when the valve is normally inoperative, the dispensing outlet of the valve is effectively sealed and when in use, communication between the supply line and the valve is closed or shut off by means actuated by a valve stem but movable relative thereto; the closing action being precedent to the opening of the dispensing port of the valve.

A further object of the present invention is a novel arrangement of the various elements of the valve to effectively fulfill the foregoing objects but which are so arranged as to result in the use of a combination of elements which may be durable but of such a simple character as to permit of a very economical production of the dispensing valve.

Other objects will be hereinafter set forth in the following description, which refers to the accompanying drawings, and the essential characteristics will be summarized in the claims.

In the drawings, Fig. 1 is an enlarged side elevation of a preferred form of valve; Fig. 2 is a cross sectional view taken centrally of the valve and showing the normal relation of the elements of the valve when the valve is closed; Fig. 3, is a similar view illustrating the relation of the various parts when the valve is in an open or discharging condition; Fig. 4 is a cross sectional view taken substantially along the line 4—4, Fig. 2; Fig. 5 is a cross sectional view taken along the line 5—5, Fig. 2; Fig. 6 is a view similar to Fig. 2, showing however, a modified form of plunger construction; Fig. 7 is a similar view illustrating the relation of the various parts of the valve when the valve is in an open or dispensing condition; Fig. 8 is a cross sectional view taken substantially along the line 8—8 of Fig. 7.

Referring to the various parts of the de-

vice by the use of reference characters, in Fig. 1, I have shown a body member 10 connected to a source of supply 11, the body member being provided with a downwardly projecting portion 12 having a suitable dispensing opening or port formed therein, communicating with the interior of the valve, as will be hereinafter described.

A piston or stem member 13 is provided with a thumb portion or push button 14 and is slidably mounted in a packing nut 15, the latter member being in threaded engagement with the outer end of the body member 10, as illustrated in Figs. 2 and 3.

The body member has a valve seat 16 formed interiorly thereof and a passageway 17 formed through the rear wall 18 of the valve body which communicates with the supply line.

A suitable mechanism for closing the opening comprises a plunger carried by the stem 13, and relatively movable thereto, and which is arranged to close communication between the supply line and the discharge chamber 20 of the valve body when the discharge bore 80 12^a is opened upon the inward movement of the stem member 13. The plunger member 19 may have a coniform head 19^a, the conic surface of which is arranged to contact with the valve seat 16 having a complementary 85 surface to the conic surface of the plunger.

To support the plunger in alignment with the inlet opening, the stem 13 is suitably bored to receive the other end of the plunger member and is maintained in operative relation therewith by a pin member 22 which passes through the inner end of the stem 13, the pin member being arranged to engage the plunger member 19 in a suitable slot 8 formed therein, whereby further inward movement of the 95 stem 13 is permitted after the stem has carried the plunger into contact with the valve seat 16. A spring member 24 is mounted on the plunger member 19 and is arranged to abut the end of the valve stem and the head 100 of the plunger member, whence the plunger member is retained in a normally extended position relative to the stem.

Opposing the inward movement of the stem is a second spring member 25, positioned 105 within the discharge chamber of the valve body with one end thereof abutting the end wall 18 of the body member, and the other end abutting a shoulder 26 formed adjacent the inner end of the valve stem 13. This 110

spring member maintains the valve stem in a normal outward position with the shoulder 26 thereof in contact with an annular packing ring 27.

5 The means for preventing leakage along the stem may comprise the packing ring 27, which abuts a shoulder formed by a difference in the bore of the valve body comprising the discharge chamber and the outer portion 10 thereof comprising the packing chamber. A metallic ring 28 is maintained in pressed relation on the face of the packing ring 27 by a spacing sleeve 29, while a flanged packing ring 30 is compressed against the end of the 15 sleeve by the packing nut 15 which is recessed to receive the cylindrical portion of the packing ring 30. It will be noted that the tightening of the packing nut 15 will compress the packing ring 30 and the packing ring 27 20 will also be compressed thereby through the sleeve 29 and metallic ring 28. The arrangement of the packing members, sleeve and nut, as well as the relation of the stem 13 thereto is described in my former application, Serial 25 No. 449,066, filed March 2, 1921.

It is to be seen in Fig. 2, that the spring member 25 maintains the valve stem in the position shown with the shoulder compressed against the inner face of the packing ring 27. 30 Since the liquid passes through this member when being dispensed, this arrangement effectively prevents any leakage of the liquid from the discharge chamber 20 to the discharge port 12 when liquid is not being dispensed. 35 The packing ring 27 will likewise serve to prevent this leakage as the plunger is moved inwardly, until a groove 9 formed in the stem, approaches the position illustrated in Fig. 3, whence communication is established 40 between the discharge chamber and the ejecting port by passage through the opening in the packing ring and through the metallic ring 28, thence through the passageways 29^a formed in the sleeve 29. The distance from 45 the shoulder 26 to the inner edge of the groove 9 is such, that as the stem 13 is forced inwardly, the plunger head will be effectively seated and close the passageway 17 from the supply line, before the groove 9 is moved to 50 the position illustrated in Fig. 3, the pressure of the plunger 19 upon the seat being equal to the pressure of the spring member 24 mounted thereon.

The diameter of the plunger member may 55 be considerably less than the diameter of the bore formed in the stem in which it moves, to allow a wobbling or shifting movement of the coniform end of the plunger when being seated on the valve seat; thus insuring a 60 proper closing of the passageway 17 before the discharge port 12^a is in communication with the discharge chamber 20 of the valve.

When manual pressure is relieved on the outer portion 14 of the stem, the stem and 65 plunger will be moved outwardly under the

influence of the spring 25 and a small quantity of liquid soap will be dispensed through the discharge port 12^a. The proportioning of the length of the stem travel to the normal distance which the plunger head 19^a is from 70 the valve seat, is such that at no time will communication be established between the discharge chamber 20 and the dispensing port 12^a before the passageway 17 is closed upon the manual operation of the valve. 75

From the foregoing description, it is to be seen that I have provided a valve having packing means which will be effective at all times in preventing leakage through the valve or along the valve stem. Furthermore, in 80 the double valve construction illustrated, the inner valve is comprised of metal parts with no resilient members involved in the construction thereof.

In Figs. 6, 7 and 8, I have illustrated a 85 modified form of construction wherein the soap being dispensed from the discharge chamber, passes through the bore of the stem in which the plunger member is slidably mounted. As shown in Fig. 6, the stem member 13^a carries a plunger member 19^a in the manner described. The fit between the plunger member and the bore of the stem however, is such that sufficient space is provided to permit the liquid to traverse the 90 bore of the stem from the discharge chamber 20^a of the body member 10 to a radial passageway 32 formed in the stem. This passageway communicates with the bore of the spacing sleeve 29^a, which is greater than the 95 diameter of the stem.

The spacing sleeve, in this case, has an annular groove 33 formed therein, which, when the sleeve is in position, spans the discharge port 12. A radial passageway 31 formed in 100 the sleeve, affords communication between the bore of the sleeve and the groove of the sleeve.

To interrupt communication between the discharge chamber and these passageways, 110 the end of the plunger 19^b which is in sliding engagement with the stem, is arranged in the form of a piston, with a pliable gasket 34 closely fitting the end thereof and also a reduced portion of the plunger formed adjacent this end. The pliable member 34 may be secured to a reinforcing metallic disc 35 by any suitable means, such as rivet 36. A 115 spring member 37 is positioned within the stem bore and acts upon the disc member to 120 maintain the pliable member 34 in compressed relation with the wall of the stem, as well as in engagement with the end of the plunger. The pin member 22^a is carried on the inner end of the stem and passes through 125 a slot 38 formed in the plunger; the pin serving to prevent the spring member 37 from completely ejecting the plunger from the stem bore. The spring member 25, in this 130 construction, functions in the manner hereto-

fore described, in reference to the construction shown in Figs. 1 to 5.

It will be noted in this case, that the liquid does not pass through the packing ring 27^a which is similar to the ring 27 in the former construction, the ring 27^a serving merely to prevent leakage of the liquid from the discharge chamber 20^a to the passageway 38. The relation of the length of the plunger to the length of the discharge chamber remains the same in this instance; there being a sufficient distance between the valve seat 16 formed about the inlet port 17 to permit the ingress of the liquid to the discharge chamber when the spring member 25 has forced the stem 13^a and consequently, the plunger 19^a, to the normal outward position, illustrated in Fig. 6.

When the stem has been forced inwardly, a distance corresponding to the space between the seat 16 and the valve end of the plunger member, the spring 37 will then be compressed as the stem is further advanced, into the discharge chamber and the packing member 34, thus being stationary, will be advanced into the bore of the stem, thereby establishing communication between the passageway 32 and the fore of the stem, whence liquid may pass from the discharge chamber 30 along the stem bore through the passageways 32, 38, 31 and 33, and through the dispensing opening 12.

It will be noted that in either of the valve constructions herein set forth, the supply line is first shut off from the dispensing valve by valve mechanism which does not operate to dispense the soap from the discharge chamber of the valve but is operated by the discharging means. Likewise, at no time will a clear path from the supply line to the discharge orifice of the valve be open, for the supply line to the valve is necessarily first closed before the discharge port is opened. Likewise, upon an outward movement of the stem, the discharge port is closed before communication is re-established between the supply line and the valve.

Having thus described my invention, I claim:

1. In a dispensing valve, the combination of a valve body with a discharge chamber having an inlet and an outlet, a valve stem having an annular shoulder formed thereon, a packing ring comprising an end wall of the discharge chamber, means for maintaining the packing ring in contact with the cylindrical portion of the piston during a predetermined movement thereof, a spring member normally maintaining the stem with the

shoulder thereof in sealed contact with the packing ring, a plunger member carried by the stem and slidably movable relative thereto, a second spring member acting on the plunger and the stem to maintain the plunger in extended relation to the stem and with the end thereof spaced from said discharge chamber inlet, whereby the stem and plunger move as a unit upon a predetermined inward movement of the stem, said plunger member closing said inlet before said packing ring loses contact with the cylindrical portion of the piston.

2. In a dispensing valve of the character described, the combination of a body member having an inlet and an outlet, a valve stem arranged to advance into the discharge chamber, a packing ring comprising an end wall of the discharge chamber, means for maintaining said packing ring in contact with the cylindrical portion of the stem, said stem having a shoulder formed thereon and normally contacting with the face of the packing ring and sealing communication between the discharge chamber and the outlet of the body member, a plunger member arranged to close the inlet to the discharge chamber upon a predetermined movement of the stem, said plunger member being carried by the stem, a spring member acting upon the plunger member and the stem, whereby relative movement between the plunger member and the stem may be permitted, and means for maintaining the plunger member in slidable engagement with the stem.

3. In a dispensing valve, the combination of a valve body provided with a discharge chamber having an inlet and an outlet, a valve stem arranged to advance into the discharge chamber, a packing ring in contact with the cylindrical portion of the stem, said stem having a portion of less diameter than the diameter of the portion contacting with the ring and having a shoulder formed thereon normally contacting with the face of the packing ring, resilient means for maintaining the stem in a normally outward position, a plunger member slidably mounted on the piston and arranged to close said discharge chamber inlet upon an inward movement of the stem, said closing action of the plunger member preceding the loss of contact between the packing ring and the stem, whereby the inlet to the discharge chamber is sealed precedent to the opening of the outlet thereof by the stem.

In testimony whereof, I hereunto affix my signature.

ALBERT R. GOLDRICK.
